AUTOMATIC APPARATUS FOR FEEDING
LIQUID OR GASEOUS MATERIALSElmer E. Harper, Monrovia, Calif.; Esther Pardee
Harper executrix of Elmer E. Harper, deceased

Application January 18, 1945, Serial No. 573,415

11 Claims. (Cl. 222—58)

1

This invention relates to apparatus for feeding or dispensing materials, especially chemical materials of liquid or gaseous form, such as chlorine gas, ammonia gas, etc., and with particular reference to the feeding of such materials by weight.

Accordingly, a primary object of the invention is to devise a feeding construction having means for feeding such gaseous or like material at an approximately uniform flow rate, together with a gravimetric type of control mechanism for making such corrections in said feeding rate as will result in producing also a substantially uniform gravimetric flow.

For accomplishing this essential purpose of the invention, I have devised apparatus which includes feeding means of the character indicated, in combination with a scales system serving to support the supply of gaseous or liquid material, and also an improved arrangement of means, responsive to fluctuations in the scales mechanism, for transmitting the necessary control action for maintaining a substantially uniform gravimetric flow of the material.

It is also an object of the invention to provide apparatus having the various improvements referred to, but which is not necessarily confined to gravimetric operation.

A further object of the invention is to devise a feeding and flow regulating apparatus in which a novel construction is provided for affording a visible indication of the flow at a considerable distance.

An important further object of the invention is to provide a duplex form of valve mechanism and control therefor as a part of the flow regulating means, whereby an auxiliary safety valve feature is provided in combination with the automatic regulating means, and said safety valve being also subject to automatic as well as manual control.

It is also an object of the invention to provide an extremely simple as well as compact arrangement and construction, the various parts of which are readily accessible, either for manual adjustment or regulation, as may be required.

With the foregoing general objects in view the invention will now be described by reference to the accompanying drawings wherein is illustrated one practical form of construction found suitable for the embodiment of my proposed improvements, after which those features and combinations deemed to be novel and patentable will be particularly set forth and claimed.

2

In the drawings—

Figure 1 is a schematic elevation illustrating a portion of chemical feeding apparatus comprising a construction and arrangement suitable for the practice of the present invention; and

Figure 2 is a similar view of the remaining portion of said apparatus, including the gravimetric control mechanism.

The prevailing practice as regards the metering and feeding of chlorine gas and the like has been to feed from a container of the material mounted on scales mechanism, and control the delivery therefrom by volumetric measuring means, and checking the results at intervals by observing the loss of weight in the container. Such practice is objectionable on various grounds, because of inaccuracies arising from temperature and barometric changes, as well as internal pressure fluctuations, in addition to numerous mechanical defects necessarily arising from such operation.

In the feeding of dry chemical materials, gravimetric feeding apparatus has been developed which is characterized by a more accurate and uniform feeding rate, and one of the important objects of the present invention is to provide improved apparatus for the feeding of liquid or gaseous materials with substantially the same degree of accuracy and efficiency, as well as equally reliable control or regulation, as has been attained by corresponding apparatus developed for the feeding of dry materials.

Referring now to the drawings in detail, the improved arrangement and construction is illustrated as comprising a container 10 for the supply of material, which may if desired be housed within a suitable cabinet 11. This receptacle or container 10 is fitted with a valve 12 from which a flexible pipe or tubing 14 leads to a duplex valve assembly made up of two valves 15 and 17 arranged in series, and each valve having a control or regulating arm 20 and adjustable stop screw 22, as well as compression spring 24 tending normally to close the valve to an extent limited by the adjustment of the corresponding stop screw 22.

From the valve 17 the outlet is by way of a flow pipe 26 extending upwardly through a block or plate 28 shown mounted at the top of the cabinet 11 and serving as the supporting base of a glass bell jar 30, the lower edge of which is seated in a fluid tight relation within a groove or channel 32 in said base, and firmly secured in this relation by means of a tie bar 33 clamped 55 against the top of the jar where the ends of

said bar are engaged by nuts 34 at the upper ends of anchor rods 35 which have their lower ends retained by nuts 36 engaging the under face of said supporting base 28.

The flow pipe 26 terminates at the upper interior of the bell jar chamber 30, which also encloses a transparent bell float member 40, which in turn encloses the upper open end of a vacuum pipe connection 42 carrying a disk element 44 for guiding engagement with the interior of said bell member 40.

The vacuum pipe 42 connects with a water jet form of eductor device 46 having a water supply connection 48 and valve 49, and also a discharge outlet pipe 50 for the discharge of the outgoing gas and water mixture.

One object in the use of such an eductor device in connection with the discharge, is to maintain a partial vacuum or negative pressure condition in the carrying out of the control operation, as a safeguard against any leak in the system, which would result only in drawing in air to be mixed with the chlorine gas; that is to say, any leak in the system would be inward rather than outward. While this might involve a possible reduction in the feeding rate of the gas, pending repair of the leak, it would be preferable to an objectionable escape of the chlorine which might result from a reliance on a feeding pressure as maintained at the source of said gas supply.

The water supply pipe 48 is provided with a branch connection 51 controlled by a valve 52 and a float element 54 for supplying water to a constant level float box 56 having an overflow outlet 57, and into which float box or chamber 56 a combination water supply and overflow connection 58 extends from the bell jar chamber 30 and from within the lower portion of the float member 40. The bell float member 40 is provided with a wire harness structure 60, the ends of which are secured by a suitable link 62 at the top of said member and adapted to freely support the same upon the upper end of said water supply and overflow pipe 58. To this harness structure 60 is attached a lifting wire 64, the lower end of which is attached to a vacuum breaker cup 66 which encloses the lower end of the pipe 58, and the latter also carries a vent bell 68 which in turn encloses the cup 66 and is provided with a safety vent outlet 70.

The valves 15 and 17 are controlled by means of bell float members 72 and 74 respectively, which are located in partly submerged relation in said float box or chamber 56. For this purpose the arm 20 of the valve 15 is provided with a link 76 connecting it with the float member 72, and the regulating arm of the valve 17 is also provided with a link 77 connecting it with an operating lever 78 fulcrumed at 79 and attached to the top of the other float member 74. The upper portion of the float member 72 is also provided with a flexible vacuum transmitting tube 80 which leads to the upper interior portion of the bell jar chamber 30, as illustrated in Figure 1.

While the float bell 72 and its connections provide a valve control means responsive to changes in the vacuum action produced in the bell jar chamber 30, the other float bell 74 forms part of an independent control mechanism operating on the gravimetric principle. The mechanism for this purpose will now be described.

A secondary water jet or eductor device 82 is provided, having a pipe connection 84 with the water supply and also an overflow pipe connection 84' with the float box 56, and also a vacuum

tube connection 85 leading to a control valve device 86 provided with a thin-edged valve seat defining an air inlet orifice 88 which is controlled by a rocker type of valve member 90 including an operating arm 91, a construction which is in all respects similar to that illustrated in my copending application Serial No. 539,049 filed June 7, 1944, now Patent No. 2,459,700, dated Jan. 18, 1949. As shown in Figure 1, the tube 85 is provided with a branch 85' leading from the interior of the float bell 74, where it has an inlet orifice near the upper interior of said float member.

The container 10 is provided with a bail 95 and supporting link 97 suspended from a pivot point 98 on a scale beam 100 carried by a fulcrum point 102 conveniently mounted inside the first cabinet member 11, as illustrated in Figure 2. The scale arm of this beam 100 is provided with a fulcrum 105 for a link connection 106 to a fulcrum point 107 on a second balanced control beam 108 which is carried by a fulcrum point 110 also supported on the interior of said cabinet—as by means of a fixed hanger member 112. On one arm of which control beam is suspended a link 114 in position for supporting engagement with the arm 91 of the valve member 90.

This control beam 108 is further provided with means for the transference of weight material from one to the other side of its fulcrum point, as an unbalancing function, in all essential respects similar to the means fully described in my copending application Serial No. 529,765 filed April 6, 1944, now Patent No. 2,416,994, dated March 4, 1947. As illustrated, this weight transferring means comprises a pair of receptacles 118 and 119, supported by links 120 from pivot points 122 on the control beam 108 at opposite sides of its fulcrum center 110, and designed to accommodate the transfer of suitable chain-weight material 124 from the receptacle 118 to the other receptacle 119 at a uniform rate, as by means of a synchronous clock motor 126 having a drive wheel 128 engaging and driving said chain weight material, which travels over idler wheels 130 during said transferring operation.

A drive connection 132 is also preferably provided from the motor shaft to a conventional counter device 134 constructed to register both batch readings 136 as well as total or cumulative readings as indicated at 138 in Figure 2. The shaft 135 of said counter device may also be provided with a crank 140 for reversing the chain transferring operation by hand, in order to rewind the chain-weight material 124 back from the receptacle 119 into the first receptacle 118 at the end of each so-called batch count, said drive wheel 128 being unclutched from its drive relation with said motor 126 in any conventional manner during such reversal of the movement of the chain material 124.

In preparation for the operation of the apparatus, the various valves 12, 15, 17 and 49 are all closed, and the tare weight of the container 10 is properly offset by means of the adjustable poise 101 on the scale beam 100, the other poise 103 being set at zero. The scale beam 100 and the control beam 108 are then balanced by a transfer of chain weight material 124 (by means of operation of the crank 140) to the chain receptacle 118, and the batch reading on the counter device 134 will also be set at zero reading.

With the motor 126 restored to engagement with the drive wheel 128, the valve 12 is opened, and then the valve 49 is also opened and the

motor 126 started for operating the chain-transferring mechanism, from which time the rate of the gas feeding action will be determined by the speed at which the chain-weight material is transferred to the receptacle 119, which will therefore be entirely automatic as well as gravimetric, in view of the automatic control devices constituting the aforesaid improvements.

The operation of the eductor device 46 produces a partial vacuum in the bell jar chamber 30, whereby a continuous flow of water is maintained, upward through the water connection 58 into said bell jar—the difference between the water levels in said jar and the float box 56 representing approximately the degree of vacuum which is maintained, and this being fairly constant during the normal feeding action when once established. Since the influence of this vacuum is transmitted through the tubular connection 80 to the float bell 72, this will result in filling both said float member and the connection 80 up to the same level as the bell jar 30, and consequently produce a sufficient pull on the arm 20 of the valve 15 to open said valve, thus opening the gas flow up to the valve 17.

The opening of the valve 49 starts operation of both eductor devices, but the normal setting or adjustment of the valve 90 is such as to admit sufficient air to prevent the development of a working vacuum in the bell float member 74 strong enough to open the valve 17 so long as the scale system is in a balanced condition. However, the operation of the motor 126 and chain transferring mechanism, by gradually transferring weight material to the receptacle 119, imparts a continuous unbalancing action to the scale system, tending to lower the link 14 and valve arm 91 and thereby allowing the valve 90 to move into more nearly closed position. This has an air-choking effect on the pipe connections 85 and 85' leading to the eductor 82 and the float member 74, and consequently this permits the eductor action to build up a stronger vacuum action within said float member 74, with corresponding lowering movement of said member and hence a downward pulling action on the connection with the arm 20 of the valve 17, which is thereby opened to allow the gas to flow on through the pipe 26 to the bell jar 30.

Thereafter, as the process continues, the operation of the valve 17 will be automatically regulated, for controlling the gas flow, in exact accordance with the rate at which the scale system tends to be unbalanced by the operation of the chain-weight transferring mechanism.

The gas entering the bell jar chamber 30 fills the space therein outside the float member 40, with the result that a differential pressure is developed which forces the gas to escape by the only possible outlet, or by way of said float member, which it enters by a bubbling action as it emerges inward past the lower margin of said member. This bubbling effect is plainly visible for distances upwards of fifty feet. From the interior of the float member 40 the gas is withdrawn of course by the eductor action by way of the ports 43 in the pipe 42 and, along with some flow of water from the bell jar chamber 30, is discharged by said eductor action out through the pipe 50.

It will therefore be understood that, after the feeding operation has once been started by the opening of the valves 12 and 49, and starting of the chain-weight transferring mechanism, a uniform flow rate, by weight, will be immediately thereafter established by the automatic operation.

of the control beam 108 and the valve 86, and the float-operated connections therewith to the valve 17.

This flow is readily observed by virtue of the bubbling action taking place in the float member 40, whereby the minutest flow movements are indicated; and by suitable illumination this bubble effect may be rendered visible for distances up to a hundred feet.

10 Provision is also made for safeguarding against abnormal pressure conditions; for example, in case sufficient vacuum should be developed in the pipe 42 for raising the water level to an undue height in the bell jar chamber 30, the float member 40 will be lifted, thereby acting, through the wire connection 64, to lift the cup 66 somewhat above the water level in the float box 56, for breaking the vacuum. Likewise any excess of positive pressure in the bell jar chamber due to 20 valve leakage, would be at once vented out through the pipe 58 to the vent bell 68 and its outlet 70. Of course the possibility of any excess water pressure in said bell jar chamber is eliminated by virtue of the large overflow outlet provided by said pipe 58.

Further provision is made to prevent the continuance of any faulty scale operation from any cause, which would result in an excessive unbalancing action and thereby operate through a connection 142 to a suitable electric switch 143 for either interrupting the motor circuit 144 or actuating an alarm or some conventional form of control device, as will be readily understood.

With reference to the provision of the duplex 35 form of valve and valve control mechanism for the flow pipe line 14, it is desired to point out that a very important safety function is served by this combination of valves. Where a valve, such as the valve 17, is subject to more or less 40 continuous operation, the wear on the valve may eventually prevent its functioning to completely shut off the flow, whereas an auxiliary valve, such as the valve 15, which is normally in wide open position, is subject to comparatively little 45 wear, and hence can be always depended upon to function satisfactorily as a positive shut off valve, even after long use. Moreover it is particularly important in gravimetric operation to make proper provision for an effective and complete shut off of the gas flow, especially in chlorine operations, and to do this automatically, as in the event of interruption of the water supply, or of vacuum failure, etc.

It will therefore be apparent that I have devised a practical and highly efficient arrangement and construction of apparatus for the carrying out of the various objects of my invention as aforesaid. At the same time it will be obvious that the illustrated construction may be very materially modified in various respects to conform to varying requirements of local conditions. For example, various features such as the valve 15 and its control connections, as well as certain of the safety provisions, may be dispensed with and still permit the maintenance of an efficient gravimetric control operation. Moreover, other gravimetric control means, such as the granular or shot-weight type of mechanism illustrated in my copending application Serial No. 535,975, filed

70 May 17, 1944, may be substituted for the chain-weight type herein illustrated, with satisfactory results; or, a modified form of fluid-pendulum control, of the character illustrated in my copending application Serial No. 535,976 filed May 17, 1944, now Patent No. 2,422,352, dated June

7
 17, 1947, might be substituted for the rocker type of valve control herein shown. Even a form of gravimetric control system, such as shown in my patent No. 2,080,267 dated May 11, 1937, might also be used in lieu of that herein illustrated with satisfactory results—the use of which patented control mechanism would also dispense with the float and vacuum mechanism of the present apparatus.

I therefore desire to be understood as expressly reserving the right to make all changes or modifications which may fairly and properly be deemed to fall within the spirit and scope of my invention as defined by the appended claims.

Having thus described my invention, what I claim and desire to secure by Letters-Patent is:

1. Apparatus for the gravimetric feeding of liquid or gaseous materials, comprising a receptacle containing the material to be handled and provided with a discharge outlet, a vacuum-actuated device provided with a fluid pressure control connection and also with mechanical control connections for regulating the flow through said discharge outlet, scale mechanism supporting said receptacle, and means responsive to fluctuations in said scale mechanism for automatically controlling said fluid pressure connection.

2. Apparatus for the gravimetric feeding of liquid or gaseous materials, comprising a receptacle containing the material and provided with a discharge outlet, a float-actuated device provided with a fluid pressure control connection and also with mechanical control connections operative to regulate the flow through said discharge outlet from the receptacle, scale mechanism supporting said receptacle, and an automatic valve responsive to fluctuations in said scale mechanism for controlling said fluid pressure connection and correspondingly regulating the flow through said discharge outlet.

3. Apparatus for the gravimetric feeding of liquid or gaseous materials, comprising means providing a flow passage for the material, a valve for regulating the flow through said flow passage, a gravimetrically controlled float device provided with connections for operating said valve, an auxiliary fluid-pressure controlled valve in advance of said first valve for controlling the flow through said passage, and fluid-pressure control means provided with operating connections to said auxiliary valve for regulating the latter.

4. Apparatus for the feeding of liquid or gaseous materials comprising, scale mechanism supporting a measured quantity of the material, means providing a flow passage for the material, vacuum producing means communicating with said flow passage, means for automatically producing fluctuations in said scale mechanism at a predetermined and substantially uniform rate, means for regulating the flow through said passage in response to said fluctuations and thereby maintaining said flow at a rate substantially proportional to the diminishing weight of the material supported on the scale mechanism, and automatic flow control means in advance of said first regulating means and responsive to the action of said vacuum producing means.

5. Apparatus for the feeding of liquid or gaseous materials comprising, scale mechanism supporting a measured quantity of the material, means providing a flow passage for the material, vacuum producing means communicating with said flow passage, means for automatically pro-

8
 ducing fluctuations in said scale mechanism at a predetermined and substantially uniform rate, means for regulating the flow through said passage in response to said fluctuations and thereby maintaining said flow at a rate substantially proportional to the diminishing weight of the material supported on the scale mechanism, a valve for controlling said flow in advance of said first regulating means, and float-actuated means responsive to the action of said vacuum producing means for operating said valve.

6. Apparatus for the feeding of liquid or gaseous materials comprising, scale mechanism supporting a measured quantity of the material, means providing a flow passage for the material, vacuum producing means communicating with said flow passage, separate valves—one in advance of the other, for controlling the flow through said flow passage, individual float control devices for actuating said valves, one of said control devices being responsive to the action of said vacuum producing means, automatic means for producing fluctuations in said scale mechanism at a predetermined and substantially uniform rate, and means for regulating the other of said float control devices and the corresponding valve in response to said scale fluctuations and thereby maintaining said flow at a rate substantially proportional to the diminishing weight of the material supported on the scale mechanism.

7. Apparatus for the feeding of liquid or gaseous materials comprising, means for providing a flow passage for the material, vacuum producing means communicating with said flow passage, separate valves—one in advance of the other, for controlling the flow through said flow passage, independent float control devices for actuating said valves, one of said control devices being responsive to the action of said vacuum producing means, a fluid pressure control connection communicating with the other of said float control devices, and gravimetric control means including a valve operating automatically to control said fluid pressure connection.

8. Apparatus for the feeding of liquid or gaseous materials comprising, scale mechanism supporting a measured quantity of the material, means providing a flow passage for the material, vacuum producing means communicating with said flow passage, separate valves—one in advance of the other, for controlling the flow through said flow passage, independent float control devices for separately actuating said valves, one of said control devices being responsive to the action of said vacuum producing means, automatic means for producing fluctuations in said scale mechanism at a predetermined and substantially uniform rate, an auxiliary vacuum producing means provided with a vacuum connection to the other of said float control devices, and automatic control means including a valve responsive to said scale fluctuations and operating automatically to regulate the vacuum action transmitted to said other float control device.

9. Apparatus for the feeding of gaseous materials comprising, a vacuum chamber having a liquid partially filling its bottom portion, a gas supply line opening into the upper portion of said chamber and provided with a control valve located outside said chamber, vacuum producing means having a gas discharge line with an intake portion communicating with said chamber, a bell float member separating said gas supply and discharge lines and having its lower end 70 submerged in said liquid and spaced from the

bottom of the chamber, and float-actuated means communicating with said chamber and having connections for controlling said valve in accordance with the vacuum action of said vacuum producing means.

10. Apparatus for the feeding of gaseous materials comprising, a vacuum chamber having a liquid partially filling its bottom portion having means for maintaining a liquid level in the lower portion of the chamber, a gas supply line opening into the upper portion of said chamber and provided with a flow control valve, vacuum producing means provided with a gas discharge line having an intake portion communicating with said chamber, a bell float member separating said gas supply and discharge lines and having its lower end submerged in said liquid and in spaced relation to the bottom of said chamber, vacuum-actuated means communicating with said chamber and having connections for controlling said valve, and safety vent means controlled by said bell float member for preventing an excessive degree of vacuum being developed in said chamber.

11. Apparatus for the gravimetric feeding of liquid or gaseous materials, comprising a receptacle containing the material to be handled and provided with a discharge outlet, vacuum pro-

ducing means communicating with said discharge outlet, vacuum actuated means responsive to the action of said vacuum producing means for regulating the flow through said discharge outlet, an auxiliary control device for controlling the flow through said discharge outlet, scale mechanism supporting said receptacle, and vacuum actuated means responsive to fluctuations in said scale mechanism for regulating the 10 operation of said auxiliary control device.
